UNITED STATES PATENT OFFICE.

AXEL HARRY ANDERSON, OF FAIRMONT, WEST VIRGINIA.

RAIL-SUPPORTING ELEMENT.

1,408,427.

Specification of Letters Patent. Patented Mar. 7, 1922.

Application filed October 20, 1921. Serial No. 509,035.

To all whom it may concern:

Be it known that I, AXEL HARRY ANDERSON, a citizen of the United States, and a resident of Fairmont, in the county of Marion and State of West Virginia, have invented certain new and useful Improvements in Rail-Supporting Elements, of which the following is a specification.

The present invention relates in general to rail supporting elements for railways and more particularly to a self locking tie for mine and industrial purposes.

The object of the invention is to provide a device of this character which is of light construction, which has no loose parts, which may be easily manufactured of wood and steel combined when the use of steel ties is not feasible, which is easy to lay requiring no tools whatsoever and avoiding the necessity of using wooden blocks, bolts or other accessories for fastening the tie to the rail, which can be manufactured organized with the tie or separate therefrom as desired, and which is in general of simple and durable construction, reliable in operation, and easy and inexpensive to manufacture.

Other objects and advantages of the invention reside in certain novel features of construction, combination and arrangement of parts as will be hereinafter more fully described and particularly pointed out in the appended claims, reference being had to the accompanying drawings forming part of this specification, and in which:

Figure 1 is a view in side elevation, showing the preferred embodiment of the invention;

Figure 2 is a plan view, the rail being omitted for the sake of illustration;

Figure 3 is a view similar to Figure 1, showing a slightly modified form of the invention; and

Figure 4 is a plan view of this modified form.

Referring to the drawings wherein for the sake of illustration is shown the preferred embodiment of the invention, the numeral 10 designates generally a tie which is shown as consisting of channel steel but which may be an ordinary wooden tie or a tie of conventional or desired type. The rail which is designated at 11 and which includes a base section 12 having inclined top surfaces 13 and 14 is supported on the tie 10 in the usual manner and is secured in position by the rail fastening device which comprises

the present invention. This rail fastening device comprises a stationary locking member, designated generally at 15 and including a base plate 16 secured to a tie by 60 a bolt or rivet 17, and an inclined fixed locking plate 18 integral with the base plate 16 and adapted to engage the surface 14 of the rail base when the rail is secured in position on the tie. Upstanding bearing lugs 19 65 are integrally formed with the locking plate 18.

A rail clamp, designated generally at 20 is provided and includes a pair of arms, designated at 21 and a pair of bars 22 integrally formed with arms 21 and disposed at an acute angle with respect thereto so as to extend around the rail as shown in the drawing. The rail clamp is pivotally mounted on the upstanding lugs 19 by 75 means of a pivot bolt 24 which is carried by the upstanding lugs and which pivotally supports the free ends of the arms 21. The arms 21 and the bars 22 lie on the outside of the tie and when the rail is secured in 80 position on the tie the bars 22 are snugly engaged with the opposite sides of the tie, as shown in Figure 2.

A movable locking member, designated generally at 25 coacts with the fixed locking member 15 to secure the rail in position on the tie and preferably the movable locking member comprises a base plate 26 extending between and integral with the bars 22 at the free end thereof, and an inclined locking plate 27 integral with the base plate 26 and engageable with the top surface 13 of the base section of the rail to secure the rail in position. In this manner the movable locking member is carried by the rail 95 clamp.

In operation when the rail is to be placed in position on the tie, the rail clamp and the movable locking member are swung up around the pivot bolt 24 to the position 100 shown in dotted lines in Figure 1. The rail 11 is then placed on the ties. As shown in dotted lines in Figure 1 one of the side edges of the base section of the rail is engaged with the ties and the other side edge is 105 spaced from the locking plate 27. The rail clamp and the rail are then swung down toward the tie in a counterclockwise direction as viewed in Figure 1 until the under side of the base section rests on the tie and the 110 top surface 14 of the base section engages the fixed locking plate 18 of the stationary

locking member. Then as the rail clamp reaches the full locking position shown in full lines in Figure 1 with the bars 22 engaging the sides of the tie the locking plate 27 engages the top surface 13 of the base section of the rail and completes the securing action. When the rail and the rail clamp are positioned as shown in full lines in Figure 1 the rail is secured in and positively locked in position on the tie and cannot be removed except by releasing the fastening means 17, as by shearing off the head of the rivet, if a rivet be used, or releasing the bolt, if a bolt be used.

15 The embodiment of the invention shown in Figures 3 and 4 is identical in all respects with the embodiment of the invention shown in Figures 1 and 2 except that the rail clamp and movable locking member are 20 constructed of a single piece of heavy round wire instead of steel plate. The stationary locking member is constructed of the same material and in all respects like the stationary locking member shown in Figures 1 and 2 25 and hereinbefore described.

The rail clamp includes a pair of arms, designated at 30, and having offset extensions 31 journaled in the bearing lugs of the stationary locking member. A pair of 30 bars 32 are integrally formed with the arms 30 and with these arms define a V-shaped seat 33 for the rail.

A movable locking member, designated generally at 35, coacts with the stationary 35 locking member as in the foregoing embodiment but is constituted by a transverse bar and connecting portions 37 integral with the transverse bar 36 and with the bars 32. The connecting portions 37 and the trans- 40 verse bar 36 engage the rail, as shown in Figure 3, after the manner in which the locking plate 27 in the previous embodiment engages the same. The operation of this embodiment of the invention is identical with 45 the embodiment shown in Figures 1 and 2 and herein-above described.

I claim:

1. In a device of the character described, a stationary locking member including a 50 fixed base plate, a fixed locking plate integral therewith and upstanding bearing lugs

carried by said fixed locking plate, a rail clamp having arms pivotally secured at one end to said upstanding lugs and bars integral with the other ends of said arms and 55 a movable locking member including a base plate secured to said bars and a locking plate extending from said base plate.

2. In a device of the character described, a stationary locking member including a 60 fixed locking plate, a rail clamp having arms pivotally connected with the fixed locking plate, and bars integral with the arms, and a movable locking member including a locking plate carried by the bars of the rail 65 carrier.

3. In combination, a railway tie, a stationary locking member including a base plate, means for securing the base plate to the tie, an inclined fixed locking plate integral with the base plate and upstanding bearing lugs carried by the fixed locking plate, a rail clamp having arms pivotally secured at one end to said bearing lugs and 70 bars integral with the opposite ends of said arms and extending angularly therefrom, the bars being adapted to lie on the opposite sides of the tie in assembly and a movable locking member carried by the rail carrier and including a base plate extending between and integral with the bars and adapted 75 to engage the top of the tie in assembly and an inclined locking plate integral with the base plate.

4. In combination, a railway tie, a fixed 80 locking plate secured thereto, a rail clamp including an arm pivotally mounted on the fixed locking plate and having a bar integral, and a movable locking plate carried by the bar of the rail clamp. 85

5. In a device of the character described, a stationary locking member, a rail clamp constructed of a single piece of wire having arms pivotally supported on the stationary locking member, a pair of bars integral with 90 the arms and extending angularly therefrom, and a movable locking member carried by the clamp and including a transverse locking bar and connecting portions between the locking bar and the pair of 100 bars.

AXEL HARRY ANDERSON.
